RAIL.

1,153,989.

Specification of Letters Patent. Patented Sept. 21, 1915.

Application filed March 13, 1915. Serial No. 14,138.

To all whom it may concern:

Be it known that I, JAMES C. Woods, a citizen of the United States of America, residing in Lockport, county of Niagara, and 5 State of New York, have invented certain new and useful Improvements in Rails, of which the following is a full, clear, and exact description.

One of the objects of my invention has 10 been to provide a rail for railways which shall be continuous, thus dispensing with the use of fish plates.

Another object has been to provide a rail having joints so arranged that expansion 15 and contraction will be taken care of. I have also sought to provide a continuous rail in which any one section may be removed and replaced by another section without having to disturb other parts of the 20 track. Moreover, due to the two part construction of my rail, the joints between any two sections are staggered so that spreading of the rails or jarring, due to improper alinement of rail sections, is entirely over- 25 come. Furthermore, my rail is especially advantageous for the reason that, when used, bonding by means of electric wires is obviated.

My rail has the same rigidity and support 30 at each end of a section as it does in the middle thereof. In case of a broken rail in either of the sections, the other section will hold the same in position and thus avoid accidents.

35 The above objects and advantages have been accomplished by the device shown in the accompanying drawings.

In these drawings, which form part of this application, like characters of reference 40 indicate like parts throughout the several views, of which:

Figure 1 is an end, sectional elevation of my rail. Fig. 2 is a perspective view showing the rail partly assembled. Fig. 3 is a 45 sectional, end, elevation of a modified form of rail.

My rail comprises a locking member 5 and a base member 6. The base member 6 is formed with the usual flange 7 and web 50 8, rising vertically therefrom. The web 8 is of even thickness at its upper edge 9 and is provided at one side, midway between the upper edge and the flange 7, with a longitudinal rib 10. The upper face of this rib is

preferably at right angles with the side of 55 the web, and the lower face is preferably at an obtuse angle thereto.

The locking member 5 is formed with the head 11 of the rail and with a downwardly extending, supplementary web 12. The 60 supplementary web 12 is arranged preferably at the side of the center of the head 11 and is provided at its lower edge with an outwardly extending lock flange 13. This lock flange is disposed at right angles to the 65 supplementary web 12 and arranged to engage a recess 14 in the flange 7 of the base member 6. This recess 14 extends from the face of the web 8 to a point near one of the outer edges of the flange portion. The supplementary web 12 is provided with a longitudinal groove 15 provided with faces which 70 register and co-act with the faces of the longitudinal ridge 10, formed on the web 8. A reinforcement 16 is provided on the supplementary web 12 and disposed over where the groove 15 is formed. The head 11 is 75 formed on its under side with a longitudinal groove 17. This groove is situated adjacent to the inner face of the supplementary web 80 12 and is arranged to receive the upper edge 9 of the web 8. The angle of the lower face of the longitudinal ridge 10 and the thickness of the flange 13 are so designed and proportioned that, when assembling, the 85 parts may be forced together laterally. The metal in the flange 13 is sufficiently light so as to permit this portion to yield until the webs 8 and 12 are brought into contact, whereupon it will spring into the recess 14. 90

In the modification shown in Fig. 3, the head 18 of the rail is made integral with the web 8 of the base member 6. The head 18 is formed with a longitudinal groove 19, 95 which is located adjacent to the inner face of the web 8 and arranged to receive the upper edge 20 of the supplementary web 21 of the locking member of the rail.

In assembling my rail, the base member 6 100 is placed in position upon the cross ties and the locking member 5 is forced in position over the joint between two base member sections. After the two parts are assembled, the usual spikes 22 are driven into the cross 105 ties and the heads thereof will overlap the flange 13, and thus prevent any possibility of its becoming disengaged from the groove 14.

When it is desired to remove a section of the rail, because of wear or breakage, any one section of the locking portion may be removed from the track independent of the other sections by prying the flange 13 out of its recess and moving the locking member 5 around the upper edge 9 of the base member as a center.

Having thus described my invention, what I claim is:

1. A two part continuous rail comprising a base member and a locking member, said base member comprising two lateral flanges and a web, said locking member comprising a supplementary web and an outwardly extending lock flange, the web of said base member being provided with a longitudinal rib and the supplementary web of said locking member being provided with a groove 20 for receiving said rib, and means for lockingly engaging the parts of said rail.
2. A two part continuous rail comprising a base member and a locking member, said base member comprising two lateral flanges and a web, said locking member comprising a head, a supplementary web and an outwardly extending lock flange, one of said

lateral flanges being provided with a recess, said head having a groove adjacent to said supplementary web for engaging the upper edge of the web of said base member, said lock flange engaging the recess in the flange of said base member, whereby the members of the rail will be lockingly engaged.

3. A two part continuous rail comprising a base member and a locking member, said base member comprising two lateral flanges and a web, one of said lateral flanges being provided with a recess, said locking member comprising a supplementary web and an outwardly extending lock flange engaging with the recess of said lateral flange, the web of said base member being provided with a longitudinal rib and the supplementary web of said locking member being provided with a groove 45 for receiving said rib, and means for lockingly engaging the parts of said rail.

In testimony whereof, I have hereunto signed my name in the presence of two subscribing witnesses.

JAMES C. WOODS.
